CALCULATING MACHINE

Germain Justin Marie Bister, Paris, France

Application May 28, 1935, Serial No. 23,816
In France April 16, 1935

5 Claims. (Cl. 235—60)

The present invention relates to improvements in calculating machines, more particularly of the type disclosed in Letters Patent No. 1,336,904 to Hopkins in which, as in calculating machines generally, multiplication is effected as follows:

a. If desired, the first of the factors of the operation are recorded on paper by means of the keyboard of a typewriter or of the addition keyboard of the calculating machine;

b. The keys corresponding to the numerals of the other factor are actuated on the addition keyboard of the calculating machine;

c. The multiplication key (key x) is operated as well as the clutch control bar of the machine;

d. The keys corresponding to the numerals of the first factor are actuated on the multiplication keyboard.

Recording of the first factor which is necessary to avoid errors cannot, thus, be effected except by means of operation a which is independent of the operations b, c, d of the multiplication proper and which necessitates repetition, either on the typewriter or on the calculating machine, of one of the factors and the actuation likewise of the appropriate keys of the numerals in this factor.

The principal object of the present invention is to effect recording of the second factor of the multiplication by operation of a single member, such recording being wholly optional.

A calculating machine enabling the above objects to be effected has the features described in the following description and set forth in the claims annexed to the end thereof.

A calculating machine according to the invention is illustrated by way of example on the accompanying drawings, in which:—

Fig. 1 is a diagrammatic side elevation of the whole machine.

Fig. 2 is a diagrammatic plan of the machine.

Fig. 3 is a plan of the operating mechanism of the bars of the intermediate keyboard.

Fig. 4 is a partial plan of this operating mechanism.

Fig. 5 is a partial sectional elevation on the line 5—5 of Fig. 4.

Fig. 6 is an elevation showing the intermediate keyboard and the mechanism returning it to zero.

Fig. 7 is a side view of the mechanism actuated by a key of the addition keyboard.

Fig. 8 is a side view of the mechanism actuated by a key of the multiplication keyboard.

Fig. 9 is a side view of the mechanism operated by the multiplier keys and controlling the contrivance returning the intermediate keyboard to zero, and

Fig. 10 is a side view of the members operating this contrivance for returning to zero.

Fig. 11 is a side view of the members of the contrivance for returning to zero in the disengaging position.

Fig. 12 is an edge view of the vertical sliding bar.

The calculating machine illustrated diagrammatically in Figs. 1 and 2 comprises, in the known manner, a main frame 1 on which are mounted the various mechanisms of the calculating machine and on which an ordinary typewriter 2 is mounted.

The sheet of paper 3, Fig. 1, is wrapped about a roller 4 and is located above an inking ribbon 5, which is arranged to receive the inscriptions from the types of the calculating machine 1, as well as from those of the typewriter 2.

The characters of the typewriter are actuated independently of the calculating machine by the keys 7¹, 7², 7³ of the typewriter keyboard, the keys in turn actuating the type bars 230 in a well known manner.

The characters 6⁰, 6¹, 6² . . . 6⁹ of the calculating machine are slidably mounted in the calculating members such as the racks 8¹, 8² . . . 8⁹ each of which carries a series of 10 characters.

The racks are arranged in parallelism lengthwise of the machine and are slidable in the frame 1.

Arranged below the series of racks 8¹—8⁹ is a series of impact members 9¹ . . . 9⁹ each of which acts on one of the corresponding characters carried by the racks and produces the recording of this character on the roller 4. As will be more fully hereinafter explained, the position of each rack at the moment of the actuation of the impact member is determined by the manipulation of the keys 16, 18 of the machine.

The advance of the racks 8 as well as the actuation of the striking members 9, are effected by a driving mechanism comprising a constantly running electro-motor 10.

A clutch 11 controlled by the vertical displacement of a clutch finger 11 may render the shaft 10¹ of the motor 10 rigid with a crank 13, the latter entraining an oscillatory shaft 12 through the intermediary of a connecting rod 14. The vertical displacement of the clutch finger 11 is controlled (a) in part by means of a clutch key 15 through the intermediary of a bent lever 15¹ pivoted at 15² on the frame and actuating a bar 42¹ an inclined part 42² of which engages a projection 11² of the clutch finger 11 and (b) in

part by the keys 16 of the multiplication keyboard as hereinafter more fully explained.

The machine also comprises the usual transversely displaceable carriage 17 which carries a series of vertically slidable pins 117 controlling racks 8¹...8⁹. Arranged above the racks 8¹...8⁹ in a fixed frame 118 is another series of pins 119 which are vertically slidable in frame 118 and in their elevated positions are displaceable in the path of travel of abutments 108¹...108⁹ carried by the racks 8¹...8⁹.

The position of the pins 117 of the movable carriage 17 is controlled in well-known manner by the keys 18⁰...18⁹ of the addition keyboard 18 through the intermediary of levers 22 entraining the movable slides 20⁰...20⁹ the upper ends of which cause vertical sliding movement of the pins 117 (Fig. 1). The vertical pins in turn, control the displacement of the calculating members, such as the racks 8¹...8⁹ through the intermediary of pins 119 which form stops at the desired points for the abutments 108 of the racks 8¹...8⁹ (Fig. 1).

According to the present invention, the multiplication keyboard 16 itself also controls the pin carriage 17 in such a manner as to effect in addition to its ordinary function of multiplier, an optional control function which enables the inscription of the multiplier on the sheet of paper 30 to be effected at will. In consequence, any error of manipulation is immediately detected without it being necessary to make complementary calculations.

For the above purpose, movable slides 20⁰, 35 20¹, 20²...20⁹ which are actuated by the addition keyboard 18, are also actuated by the multiplication keyboard 16, in such a manner that a number can be composed in the pin carriage 17 either by means of the addition keyboard 18 40 or by means of the multiplication keyboard 16.

The movable slides 20⁰, 20¹, 20²...20⁹ consist (Fig. 5) of vertical elbowed rods, which bear under the influence of returning springs 21 on the ends of rocking levers 22⁰ to 22⁹. 45 These rocking levers 22 are actuated by the keys 18 of the addition keyboard in such a manner that when one of the keys 18⁰...18⁹ is depressed, the corresponding movable slide 20⁰...20⁹ is displaced in the direction f¹ in order to 50 actuate a pin of the pin carriage 17.

Each movable slide 20⁰ to 20⁹ has a sliding head 23 connected to the respective slide 20 by pins 124¹, 124² and slots 125¹, 125² and returning spring 26. This sliding head 23 can be actuated independently of the corresponding slide 20 by the action of the keys 16⁰...16⁹ of the multiplication keyboard. This arrangement enables on the one hand friction and resistance in transmission to be reduced to a minimum, and on the other hand the body of each slide 20 to remain in contact with the respective rocking lever 22. The permanent contact of the bent rod 20 with the rocking lever 22 assures the following advantage:—the levers are combined with a row 65 of balls 130 in a notched tube 131 leaving between the abutment ends a single passage for one extension 22' of a rocking lever 22 (Fig. 1) thus preventing the actuation of a plurality of levers at one time and should the slide 20 be raised 70 by a key of the multiplication keyboard the non-actuated rocking lever 22 would lose its support on the slide 20 and come into contact with the balls, or possibly entering between two of the latter.

Each sliding head 23 of the movable slides

20⁰...20⁹ is actuated by the corresponding key of the multiplication keyboard 16. For this purpose, bars 24⁰, 24¹, 24²...24⁹ displaced in the direction f² (Fig. 8) by the depression of the keys 16⁰, 16¹...16⁹ have on one of their faces a spur 25 (Figs. 5 and 8) against which is applied the arm 26¹ of a bellcrank 26. The other arm 26² of this bellcrank 26 is connected by an adjustable cord 27 to one end of a rocking lever 28.

The several rocking levers 28⁰, 28¹...28⁹ are pivoted on a spindle 29 in common and are suitably bent in such a manner as to apply themselves respectively against the sliding head 23 of the corresponding movable slide 20⁰, 20¹...20⁹ (Fig. 4).

The carriage 17 as moved in the direction of the arrow f⁴ (Fig. 6) by a spring 30' and returned to its initial position by the toothed segment on shaft 55. This carriage is advanced 20 step by step by the action of a detent 31 the nose of which engages with a toothed rack 32 of the carriage. The advance of the carriage 33 tooth by tooth enables such carriage to bring successively the rows of pins of the pin carriage 17 over the line along which are located the sliding heads 23 of the movable slides 20⁰...20⁹ (Fig. 4).

In order to advance automatically the carriage 33 of the pin carriage, the detent 31 influenced by its returning spring 34, is raised by a vertical sliding bar 35, (the vertical bar 35, drawn by a returning spring 37, can be actuated by all the rocking levers 22⁰, 22¹...22⁹ of the addition keyboard 18 (Fig. 6)).

According to the invention, the multiplication keyboard 16 itself controls the advance of the pin carriage 17. A transmission enables the keys 16 of the multiplication keyboard to actuate the detent 31 of the pin carriage 17. This transmission is constructed in the following manner:

The sliding bars 24⁰, 24¹, 24²...24⁹ entrained in the direction f² on depression of the corresponding key 16⁰, 16¹...16⁹ of the multiplication keyboard, displace a single shutter 38 (Fig. 9) arranged above the row of these sliding bars 24.

The shutter 38, which is horizontally arranged and may oscillate at its lower part, carries laterally at its upper part a projection 40 engaging a notch 41 in the bar 42, which controls the clutch 43 of the motor (Figs. 9 and 10).

The bar 42 carries at its end a spur 43 such that on being displaced in the direction f⁵, this spur slides along a ramp of a lever 44, which oscillates in the direction f¹². The lever 44 is connected by a link 45 to a rocking lever 46 pivoted on the frame of the machine, by a pivot 47, eccentric for adjustment. The free end of the lever 46 engages the projection 48' of a movable head 48 carried by the end of the vertical sliding bar 35.

The movable head 48 is connected to the vertical bar 35 through a sliding assembly comprising the studs 49¹, 49² carried by the movable head 48 and engaging in the grooves 50¹, 50² formed in the vertical bar 35. A retractile spring 49³ interposed between a stud 49² of the movable head 48 and the vertical bar 35 tends to draw the movable head 48 downwardly (Figs. 6 and 10).

The foregoing arrangement provides a particularly flexible actuation of the transmission and enables the vertical bar 35 to be actuated by any one of the rocking levers 22.

Moreover in calculating machines of the type described, at every actuation of the driving

mechanism, such mechanism operates a contrivance for returning to zero the pin carriage 17 in such a manner as to permit the composition of a fresh number in the keyboard.

Now it is important that the pin carriage should remain in its successive positions when it is actuated by the multiplication keyboard, notwithstanding that this keyboard effects the actuation of the clutching of the motor.

For the above purpose, the main oscillating spindle 12 carries an oscillating lever 50 the end 51 of which engages at each oscillation with a block 52 carried by a rack 53. The rack 53 gears with a toothed sector 54 carried by a vertical shaft 55. A second toothed sector 56 gears with a rack 57 fast with the frame 33 of the pin carriage 17.

In existing machines at each clutching of the driving mechanism, the oscillating lever 50 on coming into engagement with the block 52 brings back the pin carriage to normal.

According to the invention, a declutching mechanism actuated by the multiplication keyboard 16 prevents the oscillating lever 30 from displacing the rack 53 and, in consequence, prevents the return to zero of the pin carriage 17. The declutching mechanism of the present invention is controlled by the lock which blocks the keyboard of the typewriter 2.

This lock of the typewriter (Fig. 9) consists in the usual manner of a comb 58 the teeth of which are placed beneath the key levers of the keyboard 7 and thus oppose the depression of such keys.

The comb 58 can be actuated by a transmission of oscillating levers 59¹, 59², slide 60 and sliding bar 61. This sliding and elbowed bar 61 is drawn in the direction *f⁸* by a stud 62 on the clutching blade 42 (Fig. 1; Fig. 10), which is itself actuated each time a key of the multiplication keyboard is depressed, as has been explained above.

The elbowed sliding bar 61 carries a pivoted lock 63 which hooks itself by a toothed portion 64 on a fixed abutment 65 (Fig. 9), in such a manner that such lock 63 holds the elbowed bar 61 in its position blocking the keyboard 7 of the typewriter 2.

At the end of the oscillation of the driving shaft 12, an abutment stud 65 actuated by the driving mechanism through any suitable lever arrangement (not shown), applies itself against the tail 66 of the lock 63 and causes the latter to oscillate in the direction of the arrow *f⁷*, whereby the elbowed bar 61 is freed. The lock of the typewriter returns to its initial position freeing the keyboard 7 of the typewriter.

According to the invention, the elbowed bar 61 carries a driving spur 70 (Fig. 9) against which rests the end of a lever 71, keyed on a shaft 72. When the elbowed bar 61 is displaced in the direction *f⁶*, the spur 70 makes the lever 71 oscillate in the direction *f⁸*. A second lever 73 is keyed on the shaft 72 and oscillates with the first lever 71. This second lever 73 actuates an oscillating cam 74 which itself actuates the declutching mechanism of the device returning the pin carriage to normal.

The cam 74 oscillates on a fixed shaft 75 and has a profile or slideway 76 which is normally concentric with the main shaft 12 on which oscillates a lever 50. This lever 50 has a sliding finger 77 with an actuating stud 78, engaged and sliding in the slideway 76 on the lever 50 oscillating under the action of the driving mechanism.

When the cam 74 is displaced in the direction *f⁸* by the lever 73, the slideway 76 approaches the shaft 12 so that the lever 50 in oscillating in the direction *f⁹*, causes the finger 77 to slide in the direction *f¹⁰*. Such finger 77 then passes over the block 52 (Fig. 11) and the mechanism for returning the pin carriage 17 to normal is not actuated.

To sum up, the improvements in the calculating machine provided by the present invention enables the operator to imprint at will the multiplier before imprinting the product obtained, which enables immediate checking of the operation.

What is claimed is:

1. In a calculating machine, an addition keyboard comprising keys from 0 to 9, a multiplication keyboard comprising keys from 0 to 9, a pin carriage controlled by either of said keyboards and adapted to receive item settings, a stationary pin field controlled by said pin carriage, movable racks controlled by pins of said pin field, type elements carried by said racks, a platen, printing hammers and means for cycling the machine, whereby an item set up by either the addition keyboard or the multiplication keyboard is printed during a cycle of operation of the machine.

2. In a calculating machine, an addition keyboard comprising keys from 0 to 9, a multiplication keyboard comprising keys from 0 to 9, a pin carriage movable from normal position to a position corresponding to the number of keys in the item set, said pin carriage being controlled by either said addition keyboard or multiplication keyboard, a stationary pin field controlled by said pin carriage, movable racks controlled by pins of said pin field, type elements carried by the said racks, a platen, printing hammers and means for cycling the machine, whereby an item set up by either the said addition keyboard or the multiplication keyboard is printed during a cycle of operation of the machine, means for restoring the pin carriage to normal, actuated by said cycling means, and means for disabling said restoring means, said disabling means being controlled from the multiplication keyboard.

3. In a calculating machine, an addition keyboard comprising keys from 0 to 9, a multiplication keyboard comprising keys from 0 to 9, a plurality of movable slides, each of said slides being controlled by the keys of the said addition keyboard, said movable slides comprising sliding heads, transmission means controlled by the keys of the multiplication keyboard and actuating the said sliding heads of the movable slides, a pin carriage controlled by either of said keyboards and adapted to receive item settings, a stationary pin field controlled by the said pin carriage, movable racks controlled by pins of said stationary field, type elements carried by the said racks, a platen, printing hammers and means for cycling the machine, whereby an item set up by either the addition keyboard or multiplication keyboard is printed during a cycle of operation of the machine.

4. In a calculating machine, an addition keyboard comprising keys from 0 to 9, a multiplication keyboard comprising keys from 0 to 9, a pin carriage controlled by either of said keyboards, and adapted to receive item settings, a yieldable element for advancing the pin carriage, a locking pawl controlling the displacement of the said pin carriage, a vertical sliding bar controlled by the keys of said addition keyboard and actuating the said locking pawl, said vertical sliding bar

comprising a movable head adapted to engage the locking pawl, transmission means controlled by the keys of the said multiplication keyboard and actuating the movable head of the vertical sliding bar, a stationary pin field controlled by said pin carriage, movable racks controlled by pins of said stationary field, type elements carried by the said racks, a platen, printing hammers and means for cycling the machine, whereby an item set up by either the addition keyboard or the multiplication keyboard is printed during a cycle of operation of the machine.

5. In a machine of the class described a type-writer keyboard, an addition keyboard comprising keys from 0 to 9, a multiplication keyboard comprising keys from 0 to 9, a pin carriage movable from normal position to a position corresponding to the number of keys in the item set, said pin carriage being controlled by the addition keyboard or the multiplication keyboard, a stationary pin field controlled by said pin carriage, movable racks controlled by pins of said pin field, type elements carried by said racks, a

platen, printing hammers, and means for cycling the machine, whereby an item set up by either the addition keyboard or the multiplication keyboard is printed during a cycle of operation of the machine, means for restoring the pin carriage to normal, comprising a transmission provided with toothed sectors, a rack and an abutment lug; an oscillating lever actuated by said cycling means, a slideable pawl carried by the said oscillating lever, said pawl normally engaging the said abutment lug and restoring the pin carriage to normal, an oscillating guide cooperating with said pawl and adapted to displace the same upon the oscillating lever, whereby said pawl may be disabled from engaging said lug, locking means for the typewriter keyboard rendered effective by depression of multiplication keys, a system of articulated levers, the latter being controlled by the said locking means, said system of levers shifting said oscillating guide into and maintaining the same in position for disabling said pawl.

GERMAIN JUSTIN MARIE BISTER.
